UNITED STATES PATENT OFFICE.

KAARLUS VAN DOREN, OF NEW YORK, N. Y.

DESIGN FOR A BILLIARD-CUE.

SPECIFICATION forming part of Design No. 24,795, dated October 29, 1895.

Application filed August 31, 1895. Serial No. 561,154. Term of patent 7 years.

To all whom it may concern:

Be it known that I, KAARLUS VAN DOREN, a citizen of Belgium, residing at New York city, New York, have invented and produced 5 a new and original Design for Billiard-Cues, of which the following is a specification, reference being had to the accompanying drawing, which represents an elevation of a billiard-cue embodying my design.

10 The leading feature of my design consists of a billiard-cue which tapers from its front to near its rear end, and which has at its rear end a contracted neck and a narrow head that is flat on its outer end.

15 *a* represents a billiard-cue, which has a regular taper from its front to near its rear end.

From the line *e* across the rear end the handle has a curved taper in the opposite direction down to the neck *b*, and from this neck the handle increases outwardly upon a curve 20 to the narrow head *d*, which is flat across its outer end. This head *d* forms but a narrow bead across the end of the handle, as shown.

Having thus described my invention, I claim—

25 The design for a billiard cue, substantially as shown and described.

KAARLUS VAN DOREN.
